BEVERAGE VENDING MACHINE OR THE LIKE

William Heier, Warminster, Pa., assignor, by direct and mesne assignments, of fifty percent to William Heier, Harry Schwartz and Har-Wil Corporation, a corporation of Pennsylvania, and fifty percent to Automatic Retailers of America, Philadelphia, Pa., a corporation of Delaware

Filed Jan. 16, 1968, Ser. No. 10,189

Term of patent 14 years

Int. Cl. D20—01

U.S. Cl. D52—3

The left side view is substantially the same in appearance as the right side view as shown in FIGURE 2 and the bottom is without ornamentation.

I claim:

The ornamental design for a beverage vending machine or the like, as shown and described.
